ADJUSTABLE TABLE TOP

Geoffrey M. Harry, Oak Park, Ill.

Application July 16, 1952, Serial No. 299,267

12 Claims. (Cl. 311—38)

1

This invention relates to improvements in tables and more particularly to a novel adjustable table capable of a wide variety of uses.

Adjustable tables in which the table member or leaf can be arranged at varying horizontal and angular positions are quite convenient and find a wide variety of different uses, e. g. as a reading desk, a lectern, an occasional table, a bedside table, a music rack, etc. However, tables of this general character as heretofore known have not been entirely satisfactory in that they have often had only limited adjustability, have not always been sufficiently stable when the leaf is in horizontal position, and have not been capable of being compactly folded with the leaf in vertical position for completely concealing the adjusting mechanism from normal view. Consequently, they have enjoyed little or no commercial acceptance.

Accordingly, a primary object of my invention is to provide a novel adjustable table having substantial advantages over the tables of this general type heretofore proposed.

A further object of the invention is to provide a novel pedestal-supported table having a table leaf capable of being adjusted to any desired position between horizontal and vertical and which is markedly stable in all of its adjusted positions.

Another object of the invention is to provide a novel adjustable table having a wide degree of angular adjustability and which is also capable of being disposed at varying elevations.

An additional object of the invention is to provide a novel table construction of the adjustable leaf type in which the leaf can be readily folded into compact vertical position for storage and in which position the leaf effectively conceals the adjusting mechanism from normal view.

Still another object of the invention is to provide an adjustable table having a novel locking mechanism for releasably securing the table leaf in any desired adjusted position.

Further objects and advantages of the invention will become apparent from the subsequent detailed description taken in conjunction with the accompanying drawings wherein:

Fig. 1 is a side elevational view of a table constituting one specific embodiment of my invention and showing the table leaf in horizontal position;

Fig. 2 is a top plan view of the structure shown in Fig. 1;

Fig. 3 is a fragmentary side elevational view similar to Fig. 1 but showing the device in compact folded relation for storage;

2

Fig. 4 is a fragmentary side elevational view showing the table leaf in one of its adjusted angular positions;

Fig. 5 is a fragmentary cross-sectional view taken along the line 5—5 of Fig. 3;

Fig. 6 is a fragmentary elevational view similar to Fig. 4 but showing a different and higher adjusted position of the device;

Fig. 7 is a fragmentary front elevational view on an enlarged scale of the upper portion of the device and showing the locking mechanism in normal locked position;

Fig. 8 is a view similar to Fig. 7 but showing the locking mechanism in released position; and

Fig. 9 is a cross-sectional view taken substantially along the line 9—9 of Fig. 7.

Referring to the drawings, the table comprises a foot or base portion 11 having a pair of oppositely extending side legs 12 (Fig. 2) and a forwardly extending leg 13 which is of greater length than the side legs 12. Extending upwardly from the base 11 is an upright post or pedestal 14 which may be suitably formed to provide any desired decorative appearance. A triangular brace 16 is provided between the post 14 and the base 11. The upper end of the post 14 is formed with a generally rectangular block portion 17 having flat sides, and a knob 18 having a flattened upper end is disposed above the block 17.

An elongated pivoted support, indicated generally at 19, extends forwardly from the upper end of the pedestal 14 for mounting the table member or leaf of the device. In this instance the support 19 comprises a pair of parallel arms 21 each having an outwardly extending straight portion 22 and an offset or curved end portion 23. The short curved ends 23 of the arms 21 are pivotally secured on opposite flat sides of the block 17 by means of a pivot pin 24 extending through the arms and the block adjacent the top of the pedestal 14.

An adjustable flat table member or leaf 26 is pivotally attached to the outer end of the support 19 by means of an attaching portion 27 secured to the underside of the leaf 26 and fitted between the outer extremities of the arms 21. A pivot pin 28 (Fig. 5) passes through the arms 21 and the attaching portion 27, and a clamp nut 29 is threaded to one end of the pin 28 for retaining the leaf member 26 in fixed relation to the support 19 when desired. A ledge or support 31 is secured adjacent the outermost edge of the table leaf 26 for supporting a book or the like thereon when in tilted position.

As will be readily apparent from the structural

relationship thus far described, the support 19 may be angularly positioned relative to the post 14 and suitable locking means, hereinafter described in detail, is provided for retaining the support 19 in any desired adjusted position. Similarly, the leaf 26 is pivotally adjustable relative to the support 19 in order to provide a wide range of adjustability in the angular position of the table leaf 26 for varying elevations thereof as determined by the position of the pivoted support 19. For rigidly retaining the table leaf 26 in desired angular position relative to the support 19, I provide a toothed rack 32 which is secured to the underside of the table leaf 26 and a swingable retainer or pawl 33 which is pivotally mounted between the arms 21 by means of a suitable pin 34. As will be evident from Figs. 4 to 6, the pawl 33 may be engaged with any desired portion of the rack 32 in order to provide a firm support for the leaf member 26. Another pin 36 is provided between the arms 21 rearwardly of the pin 34 for supporting the free end of the pawl 33 when the latter is not in use. For example, in Fig. 1 with the support 19 in horizontal position, it will be seen that the table leaf 26 is firmly supported in horizontal position by engagement with the upper edges of the arms 21 and also by flatwise engagement adjacent its free edge with the flattened knob 18. In this position of the device the rack and pawl mechanism is inactive and the pawl 33 is supported adjacent its free end by the pin 36 and is thus completely retracted within the confines of the arms 21.

Referring now to Figs. 7 to 9 in particular, the preferred form of locking mechanism for releasably retaining the pivoted support 19 in any desired position will now be described. The locking mechanism is mounted on a generally U-shaped bracket or support, indicated at 37, having a flat base portion 38 and a pair of oppositely disposed flanges or side portions 39. The bracket 37 is secured to the upright post 14 by means of a plurality of screws extending through the base portion 38 into the rectangular block 17, the base of the bracket being received in a suitable recess 42 (Fig. 9) which is provided in the front face of the block portion 17. The bracket sides 39 are each provided with a pair of inwardly extending upper and lower apertured bosses 43 and 44 respectively. The bosses 43 are in axial alignment for slidably supporting a shiftable locking pin 46, and the bosses 44 are likewise arranged to receive a companion locking pin 47.

The inner curved or offset end portion 23 of each of the arms 21 is provided with a circular recess 48 (Fig. 7), and a circular plate 49 is fastened in the recess by means of a plurality of screws 51 (Fig. 9), the recess 48 being of the same depth as the thickness of the plate 49 so that the inner surface of the plate 49 is flush with the inside surface of the arm 21. In addition, the offset portion 23 of each arm 21 has a circular end contour so that the circular plates 49 are disposed concentrically and in alignment with the end portions 23 of the arms 21. Each of the plates 49 is provided with a plurality of circumferentially arranged apertures 52 in alignment with a plurality of complementary bores 53 in the end portions 23 of the arms 21, the recesses 52-53 thus defined being arranged at the same radial distance from the pivot 24 as the pins 46 and 47. Each of the plates 49 is also provided with a central aperture 54 through which the opposite ends of the pivot pin 24 extend into the arms 21.

The shiftable pins 46 and 47 have a prede-

termined length such that they can be selectively positioned to project from the bracket sides 39 into the aligned openings 52 and 53 for retaining the arms 21 in any desired angular position relative to the upright post 14, or the pins 46 and 47 can be retracted (Fig. 8) so that they are within the confines of the bracket 37 in order to permit pivotal adjustment of the arms 21. For manipulating the pins 46 and 47, I provide a pair of parallel pivot plates or levers 56 which are supported for rocking movement about a central pivot or stud 57 which is in turn rigidly secured in a boss or socket 58 (Fig. 9) extending forwardly from the base portion 38 of the bracket. The upper and lower end portions of the parallel plates 56 are thus disposed on opposite sides of the locking pins 46 and 47 and are operatively secured to the latter by means of a pair of transverse thrust pins 59 which extend through the locking pins and have their opposite ends received in suitably elongated slots 61 in the plates 56. A helical spring 62 surrounds the pin 47 and is interposed intermediate the lower portion of the plates 56 and the left-hand boss 44, as viewed in Figs. 7 and 8, for normally urging the pivot plates 56 in a counter-clockwise direction. As will be seen in Fig. 7, the spring 62 thus causes the lower pin 47 to project outwardly to the right into a selected socket 52-53 in the right-hand arm 21, and in similar fashion the pin 46 is caused to extend into a corresponding socket in the left-hand arm 21 thereby rigidly retaining the entire pivot support 19 in desired angular position relative to the post 14. A stop collar 63 is adjustably secured on the pin 46 for coaction with the left-hand boss 43 in order to limit the extent to which the locking pins 46 and 47 project into the arms 21.

For releasing the locking mechanism, I provide a depending operating handle 64 which is pivotally attached at its upper end to a pin 66 extending through the plates 56 in eccentric relation to the central pivot 57 of the plates 56. As will be evident from Fig. 8, when the handle 64 is pulled downwardly, the plates 56 are rocked in a clockwise direction thereby retracting both of the locking pins 46 and 47 within the confines of the bracket 37 so that the arms 21 are thereby rendered rotatably adjustable on the post 14. During the releasing action, the spring 62 is of course compressed and upon releasing the handle 64 the spring 62 automatically causes the shiftable pins 46 and 47 to return to locking position. It will be understood that the elongated slots 61 in the pivot plates 56 provide the necessary clearance to accommodate the slight relative shifting of the thrust pins 59 during rotation of the plates 56. By providing the recesses 52-53 in a continuous circular arrangement, it will be seen that my device permits of a wide variation in angular relation between the arms 21 and the post 14.

By reason of the double pivoted arrangement through which the support 19 can be adjusted relative to the post 14 and the table leaf 26 can be adjusted relative to the support 19, the device is capable of a wide variety of uses. For example, in Fig. 4, the table leaf 26 is arranged at an incline and the arms 21 are adjusted in downwardly extending angular position so that this arrangement is well suited for use as a reading rack or desk while seated in a chair. In Fig. 6, the table leaf 26 is likewise at an incline but the arms 21 are adjusted to an upwardly extending angular position so that the table leaf 26 is at a higher elevation. This arrangement would

be suitable for use as a music rack or other like purposes. In Fig. 1, the table leaf 26 is shown in horizontal position so that device may be used for general living room purposes or as a bedside table. It will be noted that in the Fig. 1 position, the table leaf 26 is firmly supported by reason of the engagement of the leaf 26 with the upper edges of the arms 21 and also by reason of the fact that the rear edge of the table leaf 26 rests on the flat knob 18 at the top of the upright post 14. In addition, in any of the various positions of the table it will be seen that the device is quite stable even though the table leaf 26 extends outwardly to a considerable distance beyond the axis of the post 14. The high degree of stability is accounted for by the fact that the center leg 13 of the base 11 is made somewhat longer than the side legs 12 so that the center of gravity of the device is always within the confines of the legs 12 and 13.

Another advantage of the device resides in the fact that it can be compactly folded for storage purposes, as best seen in Fig. 3. The curved or offset conformation of the arms 21 is very important in this respect since it permits the arms 21 to be disposed in a vertical position closely adjacent and parallel to the post 14. In addition, the table leaf 26 can be folded into parallel position against the arms 21. When the article is thus arranged for storage, the nut 29 may be tightened as required in order to hold the leaf 26 in the desired vertical position. It will also be seen from Fig. 3 that when thus folded the vertical height of the leaf 26 is such that when the device is viewed from the front in the usual manner, all of the adjusting mechanism is completely concealed from normal view thereby providing an attractive article of furniture even when the table is not being used. In addition, the curved or offset shape of the arms 21 contributes substantially to the range of available height or elevation to which the leaf 26 can be adjusted.

Although the invention has been described in connection with a specific structural embodiment thereof it will be understood that various modifications and equivalent structures may be resorted to without departing from the scope of the invention as defined in the appended claims.

I claim:

1. An adjustable table comprising an upright post, a pair of parallel arms pivotally secured at opposite sides of the post, a table leaf pivotally mounted adjacent one edge thereof at the outer ends of said arms, releasable locking means coacting between said post and said arms for retaining the latter in desired angular position relative to said post, a pawl swingably supported between said arms, and rack means secured to said table leaf for cooperation with said pawl whereby to retain the table leaf in desired angular position relative to said arms.

2. An adjustable table comprising an upright post, a pair of parallel arms pivotally secured at opposite sides of the post, a table leaf pivotally mounted adjacent one edge thereof at the outer ends of said arms, releasable locking means coacting between said post and said arms for retaining the latter in desired angular position relative to said post, and an elongated retainer pivotally carried between said arms and adapted to be swung outwardly from said arms into retaining engagement with said table leaf for holding the latter in desired angular position relative to the arms, said retainer being retractable

into inactive position substantially within the confines of said arms when said table leaf is in substantially parallel relation to said arms.

3. An adjustable table comprising an upright post, a pair of parallel arm pivotally secured at opposite sides of the post, a table leaf pivotally mounted adjacent one edge thereof at the outer ends of said arms, and releasable locking means mounted on said post intermediate said arms and adapted to coact with the arms for retaining the latter in predetermined angular position relative to said post.

4. An adjustable table comprising an upright post, a pair of parallel arms each pivotally secured adjacent one end thereof at opposite sides of the post, a table leaf pivotally attached adjacent one edge thereof to the outer end portions of said arms, releasable locking means mounted on said post intermediate said arms and coacting with said one end of each of said arms for retaining the latter in desired angular position relative to said post, and elongated retainer means swingably mounted between said arms intermediate the ends of the latter, said retainer means being swingable outwardly from said arms for coaction with said table leaf for holding the table leaf in desired angular position relative to the arms and said retainer means being retractable into inactive position substantially within the confines of said arms when said table leaf is in substantially parallel relation to said arms.

5. An adjustable table comprising a base with an upright post thereon, a pair of parallel elongated arms each having an offset attaching portion at one end thereof, pivot means securing the attaching portions of said arms at opposite sides of said post whereby the pivot for said arms is in offset relation with respect to the longitudinal axis of the arms, a table leaf pivotally secured adjacent one edge thereof to the outer ends of said arms, and releasable locking means coacting between said post and said arms for retaining the latter in desired angular position relative to said post, the offset pivotal connection of said arms to said post permitting the arms to be readily disposed in depending position parallel to said post and closely adjacent thereto for compact folded arrangement of the device and also increasing the range of height adjustability of the leaf when the latter is in elevated position.

6. The device of claim 5 further characterized in that said table leaf is adapted to be pivoted into parallel relation to said arms whereby the entire device can be folded compactly with the table leaf and arms in upright parallel side-by-side relation with said post.

7. An adjustable table comprising a base with an upright post thereon, a pair of parallel elongated arms each having an outwardly curved end portion disposed at opposite sides of said post, pivot means extending through said post and the curved end portions of said arms whereby said arms are mounted on a pivot axis offset from the longitudinal axis of the arms, a table leaf pivotally attached adjacent one edge thereof to the outer end portions of said arms, and releasable locking means carried on said post intermediate said arms and coacting with the curved end portions of the arms for retaining the latter in desired angular position relative to said post.

8. An adjustable table comprising a base having an upright post thereon, elongated arm means pivotally attached at one end thereof to the post adjacent the top of the latter, a table

leaf pivotally attached adjacent one edge thereof to the opposite end of said arm means, and releasable locking means for retaining said arm means in desired angular position relative to said post, said table leaf being adapted to be disposed in supporting contact with said arm means when the arm means and the table leaf are in horizontal position and the top of said post being engageable in supporting relation with the table leaf adjacent the opposite free edge thereof.

9. An adjustable table comprising a base including an upright post, a pair of elongated parallel arms pivotally secured to the post at opposite sides thereof, a table leaf pivotally mounted adjacent one edge thereof at the outer ends of said arms, and releasable locking means adapted to retain said arms in desired angular position relative to said post, said locking means comprising retractable pin means mounted on said post and adapted to coact with said arms.

10. An adjustable table comprising a base including an upright post, a pair of elongated parallel arms pivotally secured to the post at opposite sides thereof, a table leaf pivotally mounted adjacent one edge thereof at the outer ends of said arms, and releasable locking means adapted to retain said arms in desired angular position relative to said post, said locking means comprising a plurality of pins shiftably mounted on said post intermediate said arms, said arms being provided with a plurality of openings for receiving the ends of the pins in locking relation, spring means normally urging said pins into locking position in said openings, and manually operable means for retracting said pins from said openings to permit pivotal adjustment of said arms relative to the post.

11. An adjustable table comprising a base including an upright post, a pair of elongated parallel arms pivotally secured to the post at opposite sides thereof, a table leaf pivotally mounted adjacent one edge thereof at the outer ends of said arms, and releasable locking means adapted to retain said arms in desired angular position relative to said post, said locking means comprising a bracket rigidly affixed to said post intermediate said arms, a pair of locking pins slidably mounted

on said bracket and disposed transversely between said arms, spring-pressed lever means pivotally mounted between said locking pins and operatively connected to the latter for urging the pins in opposite directions whereby the outer end portions of the pins are normally extended beyond said bracket, said arms each being provided with a plurality of openings for receiving the projecting end portions of one of said pins in locking relation therewith, and manually operable means connected to said lever means for retracting said pins whereby to permit angular adjustment of the arms relative to said post.

12. An adjustable table comprising a base including an upright post, a pair of elongated parallel arms each having an offset portion at one end and disposed on opposite sides of said post, a pivot extending through said post and the offset portions of said arms for swingably securing the arms to the post, a table leaf pivotally mounted adjacent one edge thereof at the outer ends of said arms, the offset portions of said arms being provided with a plurality of openings arranged circumferentially on a predetermined radius with respect to said pivot, and releasable locking means adapted to retain said arms in desired angular position relative to said post, said locking means including a pair of transverse slidable pins operatively supported on said post intermediate said arms at the same radial distance from said pivot as said openings whereby said pins are adapted to extend outwardly from the post into selected openings in said arms for retaining the latter in said desired angular position.
